CLAIM

The design for a desktop charger, shown and described.

DESCRIPTION

FIG. 1 is a front elevational view of a desktop charger showing my new design;

FIG. 2 is a right side elevational view thereof with the device to be charged shown in phantom, the left side elevational view being a mirror image;

FIG. 3 is a rear elevational view therof;

FIG. 4 is a top plan view thereof; and,

FIG. 5 is a bottom plan view thereof.

The phantom line showing device to be charged in FIG. 2 is included for the purpose of illustrating environmental structure only and forms no part of the claimed design.
